UNITED STATES PATENT OFFICE.

JOHN RALSTON, OF MANSFIELD, OHIO.

IMPROVEMENT IN SPRING BED-BOTTOMS.

Specification forming part of Letters Patent No. 132,982, dated November 12, 1872.

To all whom it may concern:

Be it known that I, JOHN RALSTON, of Mansfield, in the county of Richland and State of Ohio, have invented a new and useful Improvement in Spring Bed-Bottom, of which the following is a specification:

Figure 1 is a vertical longitudinal section of my improved spring bed-bottom. Fig. 2 is a detail cross-section taken through the line *x x*, Fig. 1; Fig. 3 is a detail cross-section taken through the line *y y*, Fig. 1.

Similar letters of reference indicate corresponding parts.

My invention has for its object to furnish an improved spring bed-bottom, simple in construction, strong, durable, not liable to get out of order, and convenient and comfortable in use; and it consists in the combination of the upper and lower spring-slats, the coiled springs and cross-bars with each other and with the frames, and in the combination of the end cross-bars, blocks, and spring cross-bars with the frame and with the upper and lower spring-slats, the coiled springs, and cross-bars, as hereinafter more fully described.

A is a box or frame, which is made of such a size as to fit into and be supported by the bedstead. *B* are the lower spring-slats, the middle parts of which pass below and are secured to a cross-bar, *C*, the ends of which are secured to the lower edges of the side bars of the frame *A*. The spring-slats *B* pass above and rest upon two cross-bars *D* attached to the lower edges of the side bars of the frame *A*, upon the opposite sides of, and a little distance from, the central cross-bar *C*. The ends of the spring-slats *B* are attached to the lower sides of the cross-bars *E*, which are made of such a length as to pass between the side bars of the frame *A*, and to the upper sides of which are attached the ends of the upper spring-slats *F*. The middle parts of the upper spring-slats *F* are secured to the upper side of the cross-bar *G*, which is made of such a length as to pass down freely between the side bars of the frame *A*. To the lower side of the cross-bar *G* are attached the upper ends

of a series of coiled wire-springs, *H*, the lower ends of which rest upon and are secured to the upper side of the cross-bar *C*, as shown in Figs. 1 and 3. To the lower edges of the end parts of the side bars of the frame *A*, close to the end bars of said frame, are secured cross-bars *I*, to the middle parts of the upper sides of which are secured blocks *J*, concaved upon their upper sides, to which are secured the middle parts of the spring cross-bars *K*, to the ends of which are secured the ends of the spring cross-bars *L*, blocks being interposed, when desired, between said ends. The cross-bars *E* are placed at such a distance from the end bars of the frame *A* that they may work freely along the inner edges of the cross-bar *I* and spring-bars *K L*, as shown in Fig. 1. The ends of the spring-slats *B* are cut off at or near the outer sides of the cross-bars *E*. The ends of the spring-slats *F* project to, or nearly to, the end bars of the frame *A*, so as to overlap the spring cross-bars *L*.

In ordinary use the ends of the spring-slats *F* do not come in contact with the spring cross-bars *L*, but should greater weight be placed upon the bed-bottom, the ends of the spring-slats *F* will be forced down upon the spring cross-bars *L*, so that the spring-bars *K L* may assist in supporting the weight.

Having thus described my invention, I claim as new and desire to secure by Letters Patent—

1. The combination of the upper spring-slats *F*, lower spring-slats *B*, coiled springs *H*, and cross-bars *C D E G* with each other and with the frame *A*, in substantially the manner herein shown and described.

2. The combination of the cross-bars *I*, blocks *J*, and spring cross-bars *K L*, with the frame *A* and with the spring-slats *F B*, springs *H*, and cross-bars *C D E G*, substantially as herein shown and described, and for the purpose set forth.

JOHN RALSTON.
